UNITED STATES PATENT OFFICE.

ORREN S. ELLITHORP AND JOHN F. STEWARD, OF CHICAGO, ILLINOIS, ASSIGNEES TO THE WILLIAM DEERING & COMPANY, OF SAME PLACE.

GRAIN-BINDER.

SPECIFICATION forming part of Letters Patent No. 536,422, dated March 26, 1895.

Application filed April 15, 1892. Serial No. 429,291. (No model.)

To all whom it may concern:

Be it known that we, ORREN S. ELLITHORP and JOHN F. STEWARD, of Chicago, in the county of Cook and State of Illinois, have invented certain new and useful Improvements in Grain-Binders, of which the following is a full description, reference being had to the accompanying drawings, in which—

Figure 1 is a perspective view of such parts 10 of our improvement as are necessary to show its operations. Fig. 2 is a side elevation of all the parts shown in Fig. 1. Fig. 3 is a side elevation designed to show the details of construction of the tripping arm. Fig. 4 is a detail of the tripping spring and certain parts 15 with which it is connected, in section. Fig. 5 is a detail of the compressor shaft and bearing.

First, turning to Fig. 1, in which the binder frame is omitted for the sake of clearness, the 20 various parts will be pointed out.

Our binder is of the well known Appleby type, having the needle shaft A, knotted shaft B, and packer shaft C. These shafts must be considered as journaled in the usual framework. Upon the packer shaft is the pinion c, loosely mounted thereon, and the clutching device c', which are shown in detail in Fig. 3 and need no description, as they will be understood at a glance, the form being that almost universally used. Suffice it to say that the pawl c'' is arrested by a detent and released by a movement of the latter away therefrom. On the shaft B is a gear b. This is rotated by means of a pinion and an intermediate shaft, not shown, having a pinion geared into the pinion c, upon which is the spring pawl c''. Upon the shaft B is a compressor controlling cam-rim b', cut away at a certain portion to permit the compressor controlled thereby to drop.

D is a shaft having extended therefrom, in the bundle-delivery direction, the arm d', which serves as a tripping compressor arm. The shaft D is supported near its two ends; 45 at its rear end by the arm d'', and at its forward end as will be explained. On it is formed a crank d''. In order that the shaft may not be rocked so far upward as to throw the compressor out of position when being erected sharply after the completed bundle is

ejected, the stop d⁴ is applied to the bearing d² against which the crank d³ strikes.

d⁵ is an elastic yielding link, formed of various parts, all of which it is not necessary to describe, as it is one of the well known kind of compressor links. Suffice it to say, that it is elastically extensible, and is limited in the matter of shortening by a collar d⁶ on the spring rod.

E is a bell crank, having a pivot suitably supported in any convenient part of the main frame. One end of this terminates in an anti-friction roller e'. Into an eye e², at the other end is hooked the compressor link. The compressor shaft being free to rock and the 65 tripping compressor arm d' secured thereto, the latter may be lowered to permit passage therebeyond of the completed bundle, and be raised to be in a position such that the grain may be newly compacted thereagainst.

Upon the packer shaft are the cranks F, and carried thereupon are the packers G, controlled in their movements by links g and g', the latter pivoted to the support H, which in turn is secured to a flange forward of the bar I, that forms one part of the main frame. (See Fig. 2.)

The cam-rim b' is not concentric, but cam-shaped, so that as the gear rotates in the direction shown by the arrow in Fig. 2, the compressor will be forced against the bundle being bound, or at least bring stress upon the compressor spring.

J may be considered the upper surface of the binding table, and K the under surface of the breast-plate, the parts that are supported from the upper portion of the main frame with the knotted being located therebehind.

L is the needle, of well known form, secured to the needle shaft said shaft having the crank l, to which and to a wrist on the wheel b is connected the pitman l'.

So far as described the parts have no patentable difference over devices found in the older art. Our invention consists in arrangements, and combinations, and details of construction of the tripping devices, which will now be explained.

Suitably supported in the main frame is

the rock-shaft M, having an arm *m* connected thereto, extending deliveryward and reaching somewhat into the space into which the grain is compacted by the packers G—G. This arm 5 is forced to yield by the infed grain and by properly connecting mechanism to trip the clutch. As in ordinary binders the packer shaft makes a number of revolutions while the binding devices proper are performing 10 their operations, it is necessary to hold the tripping finger in the position to which it has yielded until the binding devices have returned to their home position. Ordinarily the bundle of grain does this, but in "threading up" a machine no gavel will be in the receptacle and hence we so provide that the needle, alongside of which is the trip arm, shall hold it down. Upon the side of the 15 needle is placed a pin *l*, shown in dotted lines 20 in all the figures. The end of the trip *m* nearest its hub, where secured to M, is so shaped that the pin *l* may ride along it and force it down for the purpose of keeping the 25 detent away from the clutch until the needle has returned again.

To the rear of the shaft M is secured the 30 detent N, which is an arm adapted, when the binder is at rest, to reach so near the clutching device that it engages with the pawl *c*'' of the clutch. In Fig. 3 it is shown as moved 35 away from the pawl *c*'', and the latter has been thrown by its spring so that its part *c*'' is in the path of and will be engaged by the clutch driver *c*''. In Fig. 2, however, the 40 detent is shown in its position for arresting the pawl and disengaging the clutching devices. In order that the detent may not fall too low, a projection *n* is extended from its hub in such direction as to come in contact with the 45 journal bearing of the needle shaft. The spring *n*'' is carried by the detent, preferably inclosed in a sleeve *n* which is made in one piece with the said detent. Downward through this sleeve is extended an L-shaped 50 spring rod *n*''', and preferably also passing through the spring, the latter resting upon the bottom of the sleeve. Upon the upper end of the spring rod is the adjustment nut *n*''. The hook portion of the spring rod extends 55 beneath the needle crank.

The parts last described will be readily understood by referring to Fig. 4.

When the needle is brought upward in the 55 operation of binding, the crank is lifted away from the spring rod and hence there is no stress on the spring to force the detent downward, because, as seen in Fig. 4, it is the needle crank that, by resting upon the spring rod, causes the spring to force the detent 60 downward.

It is plain that when the pressure is brought 65 upon the trip arm *m* by the accumulating gavel the resistance of the detent spring will be overcome and the clutching devices be free to engage. This done, the needle crank will be drawn upward and, moving away from the hook, the detent will no longer be held down-

ward. In threading up, which necessitates tripping the clutch and revolving the binder by hand, the pin in the needle, as before stated, will move along the curved portion of the arm near its hub and hold the detent up. An upward projection will be seen to extend 70 from the support H. Guided in its slot *h*, at its lower end and pivoted to the tripping arm 75 *m* near its hub, is a link *h*', having a notch in which the compressor shaft D is journaled. This notch may be an eye, but we make it an arch so that the parts may go together easily. Extending so as to underlie the compressor 80 shaft, is the rest *h*''.

Reference to Figs. 2 and 3 will show that the compressor shaft is confined by the support *h*'' and notch in the link *h*'. We shall treat the compressor shaft as sustained in its 85 proper position, but free to move from the packers to a limited extent.

The link *h*' will be treated merely as means for connecting the compressor shaft to the tripping arm *m*, or rather we shall treat the 90 part of the tripping arm reaching from its hub to where the link is connected, and the link, as one means for rocking the trip shaft M. The object of this connection is to control the position of the compressing arm relative to the packing devices by means that shall assist in tripping the clutch. The 95 operation of this feature will be readily seen when we consider the compressor shaft so supported that it may move from the packers 100 and so connected that it may rock the shaft and trip the clutch. We shall draw our claims to cover both this latter feature, tripping by means of the arm *m*, and also tripping by means of the bodily yielding compressor shaft 105 and the arm *m* when connected.

Our primary object is to accomplish tripping by means of the arm *m*, but to supplement the latter by a device that shall render it operative in conditions of grain that might 110 be in the least ineffective in creating sufficient pressure against it. In short, grain binders sometimes choke, even though the trip spring be made very sensitive, and should our tripping device *m* fail, the pressure of the grain 115 will eventually become so great upon the compressing arm *d*' as to force it bodily away from the packers, and through the linking device rocking the trip shaft.

We trust we have made it clear that we do 120 not trip by causing a rocking movement of the compressor shaft D, but by permitting it to move sidewise and, so connecting it to the detent that said sidewise movement may cause the tripping of the clutch.

By reference to Fig. 2 it will be seen that if the line of the center of the pitman were extended beyond the shaft B it would pass some distance below the center of said shaft. It has been explained that the trip spring is 130 drawn down by the needle shaft crank. The said crank may be considered as sustained by the trip spring and its rod. The spring, however, cannot lift the needle crank because

the latter cannot move on account of being thrust home by the pitman. When, however, the trip stop or detent N has been moved away from the pawl of the clutch, the parts 5 of the binder that were at rest are free to move forward, and the thrust of the pitman due to the lifting action of the spring when it is made tense by the upward movement of the detent N will have the effect of lifting the 10 crank and thus starting the binder forward because the pitman, being "off the center" of the crank formed by the wheel on the shaft B, will by its thrusting action force the crank to move. This is an important matter because when the parts are in labor the pawl of the 15 clutching devices is started suddenly forward and when the driving part c⁴ of the clutch strikes it, it is moving away; for the instant, so rapidly that the shock is not great.

20 What we claim as our invention, and desire to secure by Letters Patent, is—

1. In a grain binder, packing devices and clutching devices, in combination with a compressor shaft adapted to hold its compressor 25 arm in position to receive the packed grain, and to move the latter away by a rocking action of the shaft to permit the passage of the completed bundle, said compressor shaft sustained in a yielding bearing near the compressor end that permits it to swing, and so 30 connected to the clutching devices as to set them free when the said compressor shaft is swung by the pressure of the accumulating grain brought in by the packers, substantially 35 as described.

2. In a grain binder, packing devices and clutching devices, in combination with a compressor shaft adapted to hold its compressor arm in position to receive the packed grain 40 and to move it away by a rocking action of the shaft to permit the passage of the completed bundle, said compressor shaft sustained in a yielding bearing near the compressor end that permits it to swing, and so 45 connected to the clutching devices as to set the latter free when the said compressor shaft is swung under the pressure of the accumulating grain brought in by the packers, substantially as described.

3. In a grain binder, a tripping compressor 50 arm mounted upon a shaft in bearings that permit it to rock and permit it to swing away from the packers, said yielding bearings connected to clutching devices, all in combination with packing devices that do not yield 55 and band-placing and band-uniting devices, substantially as described.

4. In a grain binder, the clutching devices and a detent mounted upon a rock-shaft that may cause it to swing away from the clutching devices, a tripping compressor shaft mounted in bearings, one of which bearings permits the said shaft to swing away from the packing devices, and so connected to the detent supporting rock-shaft that the swinging 60 movement of the compressor shaft produces a 65 rocking movement of the detent supporting shaft, all in combination with unyielding packing devices, substantially as described.

5. In combination with the binding, packing and clutching devices of a grain binder, a tripping arm m, a tripping compressor arm d' mounted upon a rock shaft, supported in a bearing that will permit the compressor and its shaft to yield under the action of the accumulating gavel, said compressor shaft bearing so connected to the clutch detent that by its swinging movement said detent will permit engagement of the clutching devices, substantially as described. 70

6. In a grain binder, the swinging compressor shaft, having a compressor arm mounted thereon, a rocking trip shaft M, having the tripping arm m mounted thereon, said swinging compressor shaft supported in bearings linked to the said trip arm m, all combined with clutching devices whereby both the yielding movement of the compressor shaft in its bearings and the rocking movement of the tripping arm m shall produce a 85 90 rocking action of the trip shaft M, and set free the clutching devices, substantially as described.
